UNITED STATES PATENT OFFICE

ARCHIBALD L. BOLLES, OF BROOKLYN, NEW YORK

REVOLVING WINDOW SASH

Application filed July 11, 1931. Serial No. 550,111.

This invention relates to window sashes and particularly to what are known as revolving sashes; and the object of the invention is to provide an improved manner of supporting and guiding the sash frames in the window frame and especially the supplemental sash bars which are movable with respect to the bead and parting strips of the window frame; a further object being to provide the opposite sides of the sashes with supplemental rails in connection with which the sashes are pivotally supported and to the provision of projecting flanges on said supplemental rails cooperating with the parting strip of the window frame to form a pivotal mounting of said rails with respect to the window frame facilitating the free and easy action of the sashes in the frame and readily adjusting and fitting the sashes to the window frame; a further object being to provide means on the upper and lower sashes for preventing accidental opening of the sashes when in closed position; a still further object being to provide means on the pivots of said sashes for coupling the counterbalance weight chains or cords therewith; and with these and other objects in view, the invention consists in a window sash of the class and for the purpose specified which is simple in construction, efficient in use and which is constructed as hereinafter described and claimed.

The invention is fully disclosed in the following specification, of which the accompanying drawings form a part, in which the separate parts of my improvement are designated by suitable reference characters in each of the views, and in which:—

Fig. 1 is an inside view of a window frame showing one of the sashes in a partially open position.

Fig. 2 is a longitudinal, sectional view through the frame and sashes shown in Fig. 1.

Fig. 3 is a transverse, sectional view through one side of the window frame and through part of two of the sashes mounted therein, showing the pivotal mounting of one sash.

Fig. 4 is a view similar to Fig. 3 indicating one of the sashes in a swung position.

Fig. 5 is an end view of the central portion of one sash indicating the manner of attaching the counterbalance chain therewith.

Fig. 6 is an enlarged, sectional and side view of the lower corner portion of the bottom sash illustrating a latch device which I employ; and,

Fig. 7 is a partial section on the line 7—7 of Fig. 1, showing a stop employed in connection with the top sash.

In the drawings, I have indicated at 10 a window frame of any desired form and construction. At 11, I have shown the lower sash; 12 the upper sash mounted to move vertically in the frame 10 in the usual channels or guideways formed by the inner and outer bead strips 13 and 14 and the central parting strip 15.

The sashes 10 and 11 may be composed of wood as illustrated in the accompanying drawings or of any other desired construction commonly known in the art. The side rails of the upper and lower sashes include supplemental rails 16 and 17 respectively.

The rails 16 and 17, in the construction shown, are formed from sheet metal and are of channel, cross-sectional form, the crosshead of each rail having arranged longitudinally thereof an outwardly pressed arc-shaped bead 16a—17a seating in a corresponding groove formed in the outer surfaces of the side rails of the sashes to normally key and retain the sashes against swinging movement with respect to the rails. The central portions of the sashes are pivoted to their respective rails by screws 18 secured to the side rails of the sashes 11 and 12, and the heads 19 of which are disposed in the channels of the rails 16 and 17. Mounted on the

screws adjacent the heads thereof are large washers or plates 20 which form seats for coil springs 21 which are disposed between said plates and the crosshead of the rails, and normally serve to hold the sashes in tensional engagement with the rails as will be apparent.

It is also preferred that the washers or plates 20 include upwardly extending hooks 22, by means of which the chains or cords 23 of counterbalance weights may be attached to the respective sashes.

- One side flange 24—24a of each rail 16—17 respectively is arranged at right angles to the crosshead and adjacent the bead strips 13 and 14 as clearly seen in Fig. 3 of the drawings, 5 said flange terminating short of the base of the channel formed between the bead strips and parting strip, whereas the other flanges 25, 25a, of the rails 16 and 17 respectively are fashioned to form outwardly projecting 10 beads 26—26a which overlie the inner faces of the parting strip 15 to facilitate the mounting and fitting of the sashes within the window frame and also to form of the corner portions 26b, note Fig. 7, pivots which can 15 act upon the corner portions 15a of the parting strip 15 to permit slight, swinging movement of the rails 16 and 17 within and between the parting strip and the outer beaded strips 13 and 14 in the operation of swinging 20 the window sashes upon the pivots and with references to the rails 16 and 17, it being understood that the grooved portions of the side rails of the sash tensionally pass over the beads 16a—17a in this operation. 25 I also prefer to employ at the upper ends of the rails 17 and on the outer surfaces thereof, inwardly projecting stop lugs 27, which are formed from the material of the rail and operate in conjunction with the outer faces 30 of the side rails of the sash 12 to limit outward swinging movement of the upper end of said upper sash.
- It will be understood that the upper sash may be swung into the position shown in Fig. 35 2 of the drawings by exerting outward pressure on the lower portion of the upper sash; and this sash may be moved into various, angular positions to give the desired ventilation and also to facilitate the cleaning of the window pane of the sash. The lower corner portions of the lower sash 11 are each provided with latch or catch devices in the form of a pin 28 adapted to pass into an aperture 29 at the lower end of the rail 16, the pin being 40 moved into operative and inoperative positions by a handle member 30 exposed on the inner face of the sash. Each of these devices is of similar construction, and the brief description of one will apply to the other. 45 These catch devices are adapted to lock the lower sash against swinging movement when in closed position, and by releasing these catch devices, the lower sash may be swung on its pivot in the rail 16 into different angular positions with respect to the window frame for the purpose of ventilation and for the further purpose of cleaning the outer surface of the window panel. 55 It will be understood that the length of the supplemental rails 16 and 17 is equal to or substantially equal to the length of the side rails of the sashes 11 and 12, and that said rails are movable in and between the bead strips and parting strips at opposite sides of the window frame in the operation of raising 60

and lowering the sashes in the usual manner and apart from the swinging movement that may be contributed thereto. By using the supplemental rails 16 and 17, the mounting of the sashes in the window frame is facilitated, 70 and at the same time, the free and easy sliding movement of the sashes is provided.

It will also be apparent that the pivotal movement of the rails upon the parting strips facilitates the free, swinging movement of the sashes on their pivots. It will be understood that while I have shown certain details of construction for carrying my invention into effect, that I am not necessarily limited to these details, and various changes in and modifications of the construction herein shown and described may be made within the scope of the appended claims without departing from the spirit of my invention or sacrificing its advantages. 80

Having fully described my invention, what I claim as new and desire to secure by Letters Patent, is:—

1. In a window frame construction, the combination with the upper and lower sashes and the conventional parting strips of the window frame, of supplemental rails guiding the sashes in their sliding movement with respect to the frame and parting strips, 90 means centrally of the sashes for pivotally supporting the same in connection with said supplemental rails to permit swinging movement of the sashes in said rails in the different positions of the rails with respect to said frame, and the rails of each sash including outwardly projecting flange portions 95 which overlie and are in constant engagement with the outer surface and edges of the parting strips for providing pivotal mounting of said rails with respect to the parting strips of the window frame. 100

2. In a window frame construction, the combination with the upper and lower sashes and the conventional parting strips of the window frame, of supplemental rails guiding the sashes in their sliding movement with respect to the frame and parting strips, 110 means centrally of the sashes for pivotally supporting the same in connection with said supplemental rails to permit swinging movement of the sashes in said rails in the different positions of the rails with respect to said frame, the rails of each sash including outwardly projecting flange portions which 115 overlie and are in constant engagement with the outer surface and edges of the parting strips for providing pivotal mounting of said rails with respect to the parting strips of the window frame, and said supplemental rails being formed from sheet metal and being substantially channel-shaped in cross sectional form with the channels thereof directed outwardly with respect to said sashes. 120

3. In a window frame construction, the 125

combination with the upper and lower sashes and the conventional parting strips of the window frame, of supplemental rails guiding the sashes in their sliding movement with respect to the frame and parting strips, means centrally of the sashes for pivotally supporting the same in connection with said supplemental rails to permit swinging movement of the sashes in said rails in the different positions of the rails with respect to said frame, the rails of each sash including outwardly projecting flange portions which overlie and are in constant engagement with the outer surface and edges of the parting strips for providing pivotal mounting of said rails with respect to the parting strips of the window frame, said supplemental rails being formed from sheet metal and being substantially channel-shaped in cross sectional form with the channels thereof directed outwardly with respect to said sashes, means involving tensional devices for retaining the sashes against accidental swinging movement with respect to the rails, and a stop device on the upper end of the supplemental rails of the upper sash for preventing outward swinging movement of the upper end of said upper sash.

4. The combination with the beaded and parting strips of a window frame and guide channels therebetween, of supplemental rails arranged at opposite sides of the upper and lower sashes mounted in said frame and slidably movable in said channels, means involving tensional devices for pivotally supporting the sashes to said rails, each of the supplemental rails including projecting flanges overlying and constantly engaging the parting strips of said frame to retain the sashes in proper position in the frame and to provide a pivotal mounting of said rails with respect to the parting strips, and said rails being free to swing into the channels of the frame in the pivotal movement thereof.

45 5. The combination with the beaded and parting strips of a window frame and guide channels therebetween, of supplemental rails arranged at opposite sides of the upper and lower sashes mounted in said frame and slidably movable in said channels, means involving tensional devices for pivotally supporting the sashes to said rails, each of the supplemental rails including projecting flanges overlying and constantly engaging the parting strips of said frame to retain the sashes in proper position in the frame and to provide a pivotal mounting of said rails with respect to the parting strips, said supplemental rails being fashioned from sheet metal and being channel-shaped in cross sectional form and the side flanges of said channels terminating short of the bottom walls of said channels to permit free sliding and pivotal movement of said rails with respect to the window frame.

6. The combination with the beaded and parting strips of a window frame and guide channels therebetween, of supplemental rails arranged at opposite sides of the upper and lower sashes mounted in said frame and slidably movable in said channels, means involving tensional devices for pivotally supporting the sashes to said rails, each of the supplemental rails including projecting flanges overlying and constantly engaging the parting strips of said frame to retain the sashes in proper position in the frame and to provide a pivotal mounting of said rails with respect to the parting strips, said supplemental rails being fashioned from sheet metal and being channel-shaped in cross sectional form, the side flanges of said channels terminating short of the bottom walls of said channels to permit free sliding and pivotal movement of said rails with respect to the window frame, and projecting stop members at the upper end of the rails of the upper sash cooperating with said upper sash to prevent outward swinging movement of the upper end thereof with respect to said rails.

In testimony that I claim the foregoing as my invention I have signed my name this 9th day of July 1931.
